UNITED STATES PATENT OFFICE.

EUGENE J. FEHR AND WILLIAM W. DARROW, OF CHICAGO, ILLINOIS, ASSIGNORS TO CAMEL COMPANY, OF CHICAGO, ILLINOIS, A CORPORATION OF ILLINOIS.

METAL CAR DOOR.

Application filed March 3, 1926. Serial No. 91,862.

This invention relates to a metal door for railway cars and the like, and concerns itself with a structure which is simple in manufacture in that it comprises but few 5 parts and requires a much smaller number of rivets than heretofore used for assembling the same, which is sufficiently light to meet the requirements of common practice yet sufficiently rigid to prevent flexure 10 or weaving.

The invention comprises the novel structure and combination hereinafter described and more particularly pointed out and defined in the appended claims.

15 In the accompanying drawings which illustrate a preferred embodiment of this invention and in which similar reference numerals refer to similar features in the different views,

20 Fig. 1 is a front elevational view of a metal car door involving this invention;

Fig. 2 is a broken sectional view upon the line II—II of Fig. 1;

25 Fig. 3 is a broken sectional view upon the line III—III of Fig. 1;

Fig. 4 is an enlarged fragmentary elevational view showing the upper corner construction;

30 Fig. 5 is an enlarged fragmentary elevational view at the juncture of two panel sections;

Fig. 6 is a fragmentary perspective view showing the manner of connecting the reinforcing parts;

35 Fig. 7 is a fragmentary sectional view of a modified structure illustrating a lower roller support in the door.

Referring now to the drawings, it will be observed that the illustrated door comprises 40 a plurality of panel sections 1, 2 and 3. The upper and lower margins of the panel 2 are outwardly offset as indicated at 4 in Fig. 3, and the lower margin of the panel section 1 and the upper margin of the panel section 3 45 are correspondingly offset. These offset portions of the panels are riveted together by rivets 5. These offset portions tend to rigidify the door.

It will be noted that the offset margins 50 of the panel sections 1, 2 and 3 terminate a short distance from the lateral margins of the panels in order to provide space for rigidifying members 6 which extend along lateral margins of the door. Each of these rigidifying members 6 is in the form of a

channel member having a web portion 6^a spaced from the plane of the door, and laterally extending attaching flanges 6^b riveted to the door. At the upper margin of the door there is secured a similar rigidifying member 7 of channel-like formation having an intermediate portion 7^a spaced from the door and laterally extending flanges 7^b through which the attaching rivets extend. Suitable roller supporting brackets 8 are 65 attached at the upper corners of the rigidifying members 6 and 7 so as to overlap the joints.

The lower margin of the panel 3 is outwardly offset as indicated at 9 in Fig. 3 and 70 a rigidifying channel-like member 10 having upper and lower attaching flanges 10^b is riveted to the offset portion by its upper flange 10^b. A bridging strip 11 extends across the rigidifying member 10 and is 75 riveted to the lateral margins thereof. While it is possible to extend the panel 3 downwardly sufficient so that the rigidifying member 10 may be riveted by both flanges to the panel as shown in the Elliott 80 Patent No. 1,330,143, the present structure facilitates the manufacture and assembly of the door and at the same time it increases the section modulus of the lower part of the door.

In order to further stiffen and brace the door, the channel members 6 are provided with hoods or envelopes 12 that overlap the ends of the transverse channels 7 and 10 and the offset joints 4 of the panel sections 90 as shown in Fig. 6. The members 6 are preferably formed by pressing a flat sheet of metal in a die which is so constructed at intervals that the proper hoods 12 are formed for fitting over the top and sides 95 of the channels 7 and 10 and the offset joints 4. The hoods 12 are riveted to the tops of the channels 7 and 10 and to the joints 4 as indicated at 5^a.

In order to prevent lading from entering 100 the vertical spaces under the channel member 3 through the offset joints of the panel sections, guard plates 13 are positioned to close the entrance of the space defined by the offset joints to the vertical channel members 6. It will be noted that an end of each guard plate 13 is riveted to the offset ends 105 of adjacent panel sections, while the other end extends into the vertical chamber of the channel member 6.

The completed door is provided with the usual front edge angle 14 and the rear edge angle 15, and the lower channel member 10 is provided with air vents 10° whereby a circulation of air is maintained around the door beneath the channels 6 and 7 to prevent sweating and corroding in the hollow channels of the reinforcing members.

In Fig. 7 there is illustrated a lower support for the door comprising a roller 16 supported at the lower end of the door, and running upon a track 17, the outer roller bracket 18 and the track having overlapping parts 19 and 20.

It will be appreciated that the car door is made of few parts and requires less riveting than many other doors of this type. Moreover the connections between the transverse reinforcing parts and the vertical members 6 secure a rigid joint that tends to rigidify the structure. It will also be appreciated that the door can be very easily and economically manufactured.

We are aware that many changes may be made and numerous details of construction may be varied through a wide range without departing from the principles of this invention, and we therefore do not purpose limiting the patent granted hereon, otherwise than necessitated by the prior art.

We claim as our invention:

1. In a metal car door, a plurality of panel sections having their adjacent margins outwardly offset and secured together, and channel-like reinforcing members secured to

the lateral margins of the panels and having laterally projecting hoods enclosing the ends of said offset margins.

2. In a metal car door, a plurality of panel sections having their adjacent margins offset and secured together, channel-like reinforcing members secured to the lateral margins of said panel sections and having offset hoods overlapping said offset margins and guard plates at opposite ends of said offset margins to exclude lading from entering said channel-like reinforcing members.

3. In a metal car door, a panel having an intermediate outwardly offset portion, channel-like reinforcing members secured at an angle to said offset portion, the interior of said channel members communicating with said offset portion and guard plates in said offset portion to exclude lading from said channel members.

4. In a metal car door, a plurality of panel sections having adjacent margins outwardly offset and secured together, reinforcing transverse channel shaped members at the upper and lower margins of said door and vertically extending channel-like reinforcing members secured to the lateral margins of the panels and having laterally inwardly projecting hoods enclosing the ends of said offset portions.

In testimony whereof we have hereunto subscribed our names:

EUGENE J. FEHR.
WILLIAM W. DARROW.
